UNITED STATES PATENT OFFICE.

THOMAS R. AUSTIN, OF COLEMAN, TEXAS.

TYPE-WRITER.

SPECIFICATION forming part of Letters Patent No. 699,473, dated May 6, 1902.

Application filed February 3, 1902. Serial No. 92,456. (No model.)

To all whom it may concern:

Be it known that I, THOMAS R. AUSTIN, a citizen of the United States, residing at Coleman, in the county of Coleman and State of Texas, have invented new and useful Improvements in Type-Writers, of which the following is a specification.

My invention relates to type-writers; and the object of the same is to construct a device which will do away with the present platen-shift and shift-key mechanism and will enable all shifting from lower case to upper case to be done by means of the one set of keys ordinarily employed, but of modified construction.

The simple and novel construction employed by me in carrying out my invention is fully described in this specification and claimed, and illustrated in the accompanying drawings, forming a part thereof, in which—

Figure 1 is a perspective of a portion of a type-writer with my improvements thereon. Fig. 2 is a detail of one key and its corresponding key-bars. Fig. 3 is a detail perspective of one key. Fig. 4 is a detail section of the same. Fig. 5 is a detail plan of the same. Fig. 6 is a detail plan of the slide of one key. Fig. 7 is a section of a key on the line 7-7, Fig. 2. Fig. 8 is a modified form of slide having a checkered surface to prevent the slipping of the fingers.

Like numerals of reference designate like parts in the different views of the drawings.

The numeral 1 designates the frame of a type-writer having a keyboard 2. The keys 3 of the keyboard 2 are arranged in parallel rows in the usual manner. The detailed structure of the keys 3 is novel and will be described in detail. Each of the keys 3 comprises an angular body 4, a revoluble shank 5, bearing a foot 5^a and a pinion 6^a, and a head 6, bearing a sliding plate 7, carrying a rack 8, meshing with the pinion 6^a. The angular body 4 is slidably mounted in an apertured bar 4^a and is adapted to be depressed by the fingers to operate the key-levers. There are two sets of key-levers the members of which alternate and are arranged side by side. The members of one series are designated 9 and operate type-bars for the lower-case letters, while the members of the second

series are designated 10 and serve to operate type-bars 12, bearing upper-case type. The members of the series 9 and 10 are arranged in pairs bearing corresponding letters, there being one pair for each of the keys 3. The feet 5^a are set to normally engage the key-bars 9. The sliding rack-bearing plates 7 have concave depressions formed therein to accommodate the tips of the operator's fingers and enables him to give the plates a horizontal thrust to operate the shanks to rotate them to bring the feet 5^a into position to engage the key-bars 10. Springs 13 bear on the plates 7 and serve to return them to their initial position after displacement. An apertured guide-plate 14 serves to hold the shanks against wobbling. Screws 15, fitting slots 16 in flanges 14^a, serve as stops to limit the movement of the plates 7.

In operation the keys 3 are operated by the fingers in the usual manner to print the lower-case letters, when the feet 5^a will engage the key-bars 9 and operate them to actuate the type-bars 10. When it is desired to print an upper-case letter, the operator places his finger on the corresponding lower-case key 3 and pulls to him or pushes the plate 7 from him, according to construction. This action will operate the rack-bar 8 to rotate the pinion 6^a to turn the shank 5 through one-half a revolution and bring the foot 5^a into position to engage the key-bars 10. As soon as the plate 7 is brought to a standstill by the stop 15 thereon the operator presses down on the key, prints the letter, and then releases it. When the key is released, the spring 13 will return the plate 7 to its initial position.

I do not wish to be limited as to details of construction, as these may be modified in many particulars without departing from the spirit of my invention.

Having described my invention, what I claim as new, and wish to secure by Letters Patent, is—

1. In a type-writer, the combination of a type-bar bearing a lower-case letter and provided with a pivoted key-bar, a type-bar bearing an upper-case letter and provided with a key-bar, a slidably-mounted key bearing a rotatable shank bearing a pinion and a foot normally engaging one of said key-bars, and

means for rotating said pinion to bring said foot into engagement with the other of said key-bars, substantially as described.

2. In a type-writer, a pair of pivoted key-bars, a slidably-mounted key bearing a rotatable shank having a foot engaging one of said key-bars, a sliding plate carried by said key, and means operated by the sliding of said plate to rotate said shank to bring said foot into engagement with the other of said key-bars, substantially as described.

3. In a type-writer, a pair of pivoted key-bars, a slidably-mounted key bearing a rotatable shank having a foot engaging one of said key-bars, a sliding plate carried by the head of said key, means operated by the sliding of said plate to rotate said shank to bring said foot into engagement with the other of said key-bars, and a spring arranged to oper-

ate said sliding plate to restore it to its initial position, substantially as described.

4. In a type-writer, the combination, of a pair of pivoted key-bars, a slidably-mounted key having a rotatable shank bearing a foot normally engaging one of said key-bars, a pinion on said shank, a sliding plate bearing a rack-bar meshing with said pinion, and a spring arranged to actuate said sliding plate to restore it to its initial position, substantially as described.

25 In testimony whereof I have hereunto set my hand in presence of two subscribing witnesses.

30 THOMAS R. AUSTIN.
